UNITED STATES PATENT OFFICE

OLIVER S. JENNINGS, OF MANSFIELD, OHIO, ASSIGNOR TO WESTINGHOUSE ELECTRIC & MANUFACTURING COMPANY, A CORPORATION OF PENNSYLVANIA

ARC QUENCHER FOR SAFETY SWITCHES

Application filed April 5, 1928. Serial No. 267,516.

My invention relates to switch mechanisms and particularly to enclosed switch mechanism wherein the contact jaws and switch blades are enclosed within a metal housing.

5 An object of my invention is to provide an enclosed switch mechanism wherein the arc incident to the separation of the switch blade from the contact jaw is extinguished before the jaw or blades are injured by the arc.

10 A further object of my invention is to provide a switch mechanism wherein the arc incident to the separation of the switch blade from the contact jaw is transferred to an arc extinguishing member that is electrically connected to the contact jaw but which does not engage the switch blade, thereby preventing burning of the contact jaws.

A further object of my invention is to provide a switch mechanism with an arc extinguishing device somewhat similar to the device shown in my co-pending application, Serial No. 606,565, filed Dec. 13, 1922, and assigned to the Westinghouse Electric & Manufacturing Company, wherein spaced metal barrier plates are superposed over the contact jaw and are provided with slots through which the switch blade passes in moving to open or closed position, and to provide improved means for supporting the barrier plates for effectively extinguishing the arc and for directing the arc gases in a direction where they will do no harm.

25 A further object of my invention is to provide a switch mechanism having the above noted characteristics wherein the arc extinguishing barrier plates are supported upon insulating plates disposed on opposite sides of the switch jaw and supported on the arc receiving member that is connected to the contact jaw.

A further object of my invention is to provide a switch mechanism with an arc quenching device that is simple in construction and 40 which may be readily assembled and which is economical to manufacture.

These and other objects that will be made apparent throughout the further description of my invention are attained by means of the apparatus hereinafter described and illus-

trated in the accompanying drawings, wherein,

Figure 1 is a plan view of an enclosed switch embodying features of my invention, with the cover cut away to expose the switch mechanism,

Fig. 2 is a longitudinal section through the switch mechanism shown in Fig. 1, taken on the line II—II thereof, and showing the switch mechanism in side elevation and the arc extinguishing device partly in section,

Figs. 3 and 4 are plan and side elevational views, respectively, of the arc-quenching device shown in Fig. 1,

Fig. 5 is an end view of the arc-quenching barrier shown in Figs. 3 and 6 and looking in the direction of the arrow V in Fig. 6,

Fig. 6 is a longitudinal section through the barrier shown in Fig. 3, taken on the line VI—VI thereof,

Fig. 7 is a side elevation of an insulating barrier supporting plate,

Fig. 8 is a transverse section through the plate shown in Fig. 7, taken on the line VIII—VIII thereof,

Fig. 9 is an elevational view of a barrier plate shown in Figs. 3 and 4, and

Fig. 10 is a perspective view of the arc-receiving member and a portion of its supporting means.

Referring to the drawings, the enclosed switch mechanism comprises a sheet metal housing 11 that is provided with a cover 12 hinged at 13 and which is releasably retained in closed position by means of a latch 14.

A three pole knife switch is mounted within the housing and comprises an insulating base 15 upon which are mounted three pairs of switch contact jaws 16 and three pairs of hinged jaws 17 which serve to pivotally support the three knife blade switch members 18 that are movable into and out of engagement with the contact jaws 16.

The switch blades 18 are connected for simultaneous operation by means of an insulating bar 19 that is provided with an operating clip 21 having an oblong opening or slot 22 through which the operating bail 23 extends. The bail 23 is pivotally mounted in the side walls of the housing 11 and is

provided with a movable operating handle 24 by means of which the switch may be actuated from the exterior of the housing.

The operating bail 23 is yieldingly connected to the insulating bar 19 through the medium of springs 25 which serve to withdraw the switch blades from the contact jaws with a snap action after the operating handle has been moved a predetermined distance toward open position. In the event that the blades do not snap from the contact jaws before the bail 23 engages the outer end of the slot 22, the bail will positively engage the end of the slot and force the switch blades out of engagement with the contact jaws. Contraction of the springs 25 will immediately move the blades to open position with a snap action.

The above described switch is of well-known standard construction and no claim is made to the specific form of switch device herein illustrated and described.

My invention relates primarily to an improved arc-quenching device that is applicable to switch devices of the character described and also to other forms of switch devices, whether they be of the contact jaw and switch blade type, or of the clutch contact type.

Referring to Figs. 2 to 10, particularly, the arc-quenching device comprises an arc-receiving plate 26 that is of U-shape, having a pair of side plates 27 integrally connected by a barrier plate 28 having a slot 29 therein that registers with the spaces between the jaws of the contact jaw and through which the free end of the switch blade 18 passes in moving to open or closed position. The contact jaw is provided with a pair of supporting lugs 30 disposed in staggered relation that constitute integral parts of the contact jaw and which may receive attaching lugs 31 of the arc-receiving barrier member 26, the barrier 26 being detachably secured to the lugs 30 of the contact jaw by means of screws 32.

Since the arc-receiving barrier member 26 is conductively connected to the contact jaw, the arc incident to the separation of the switch blade from the contact jaw will be transferred to the plate 28 the instant the blade disengages from the contact jaw. Thus burning of the contact jaw is prevented. If the arc endures for any appreciable time, the burning action will occur at the point of contact of the arc with the barrier plate 28.

In the above-referred to patent application, I have disclosed a plurality of metal spaced plates superimposed about the contact jaw and provided with slots through which the switch blade passes in moving to open or closed positions. The purpose of the plates is to provide masses of cooling material in the vicinity of the arc which is drawn at a point

within the boundaries of the plates and which expands into the space between the plates and is cooled thereby. The plates are made of iron and the magnetic field produced by the arc tends to move the arc along the plates toward the outer ends thereof. The metal plates also produce a deionizing effect which, in the case of alternating current, prevents re-forming of the arc after it has once been extinguished as it passes through the zero voltage of its cycle of alternation.

My present invention relates to the manner of mounting the plates and supporting them by insulating members that determine the shape and volume of the space between the plates and which direct the arc gases in predetermined paths where they are rendered harmless and extinguished before they can expand to dangerous proximity to the walls of the enclosing housing.

With this object in view, I provide for each contact jaw, a pair of insulating plates 33, that are provided with marginal flanges 34 and 35 and transverse webs 36 which form recesses 37 therebetween, in which the sheet iron barrier plates 38, 39 and 41 are inserted, the insulating plates being retained in assembled position as shown in Figs. 3 to 6, when they have been riveted to the side plates 27 of the arc-receiving barrier member 26 by means of rivets 42 as indicated in Fig. 6. The plates 38, 39 and 41 are provided with notches 43 that receive the flanges 34 of the insulating plates 33 which serve to prevent longitudinal displacement of the plates. The plates are also provided with slots 44 that are aligned with one another and with the notch 29 in the arc-receiving barrier plate 28.

As indicated in Fig. 2, the plates are disposed in an angular position with respect to the insulating base 15 and are arranged in a substantially radial direction with respect to the axes of rotation of the switch blades. When the switch blade is moved to open position, the free end thereof passes through the slots 29 and 44 in the plates 28, 38, 39 and 41.

It will be noted by referring to Figs. 1, 3 and 5, that the webs 36 of the insulating plates are of such shape that they substantially close the space between the plates in the vicinity of the inner slotted edges thereof and the space between the plates, determined by the shape of the webs, expands in volume from the slotted front ends of the metal plates toward the rear ends thereof.

By reason of this construction, the arc gases generated between the plates are forced to expand rearwardly instead of toward the hinged jaw of the switch and to relieve the pressure between the plates, the insulating plates 33 are provided with side openings 45 through which gases may be discharged laterally. The rear edge of the barrier plate 28 is cut away at 46, which permits the gases between the plates 28 and 38 to expand down-

wardly into the chamber 47 and partially confined by the flanges 34. Since the plate 28 is conductively connected to the contact jaw, the polarity of the plate and jaw in the vicinity 5 of the downwardly discharged gases is the same as that of the arc and, consequently, no damage can result by the deflection of gases toward the base of the contact jaw. The gases between the plates 38 and 39 and between the plates 39 and 41 are of reduced pressure relative to those in the space between the plates 28 and 38, and since the plates 39 and 41 are of increased length, they are amply adequate to reduce the temperature 10 of the arc gases before they are discharged from the space between them.

It has been found that by reason of the use of the arc-quenching device above described, currents of relatively large value may be interrupted without causing the discharge of the arc gases from the extinguishing unit. The arc is extinguished so rapidly that practically no burning of the switch blade occurs.

Switches are usually rated by their capacity to interrupt a current without injury or destruction. The switch blades and jaws may be capable of carrying considerably more current than they are capable of rupturing. By increasing the rupturing capacity, the rating of the contacts may be materially increased without changing the contacts of the switch blades and contact jaws. By reason of the provision of the arc-quenching device, the capacity of the switches is increased without materially affecting the cost. The construction of the arc-quenching device is of such simplicity that it is relatively inexpensive to manufacture and may readily be assembled. By mounting the arc-quenching barrier plates between insulating plates that are secured to the arc-receiving barrier plate, the arc-quenching devices may be assembled and handled as a unit, which may be applied to the contact jaw after assembly. Inspection and repair of the barriers is facilitated by reason of this construction.

While I have described the arc-quenching device as applied to a knife type switch and have claimed the device as so applied, it will be understood that the terms switch blade and switch jaws, appearing in the claims, apply to any form of switch contacts.

While I have illustrated but one embodiment of my invention, it will be apparent to those skilled in the art that various changes, modifications, substitutions, additions and omissions may be made in the apparatus illustrated without departing from the spirit and scope of my invention as set forth in the appended claims.

I claim as my invention:

1. Switch mechanism comprising a contact jaw, a switch blade movable into and out of the said jaw, and a plurality of spaced metal barriers associated with the jaw and

having openings therein through which the switch blade passes in moving to open position, the barrier nearest to the jaw being conductively connected thereto for preventing the drawing of an arc between the blade and the jaw. 70

2. Switch mechanism comprising a contact jaw, a switch blade movable into and out of the said jaw, a plurality of spaced metal barriers associated with the jaw and having openings therein through which the switch blade passes in moving to open position, the barrier nearest the jaw being conductively connected thereto, and insulating supports carried by the last said barrier for supporting 75 the other barriers. 80

3. The combination with a contact jaw and a switch blade movable into and out of contact therewith, of an arc-quenching device comprising a plurality of metal plates spaced apart and provided with aligned slots extending inwardly from one edge and through which the blade passes, and insulating means between the plates providing an enclosed space expanding in volume from a point adjacent the slotted end of the plates toward the opposite end thereof. 85 90

4. The combination with a contact jaw and a switch blade movable into and out of contact therewith, of an arc-quenching device 95 comprising a plurality of metal plates spaced apart and provided with aligned slots extending inwardly from one edge and through which the blade passes, and an insulating support for the barriers comprising means of insulating material having an inner surface extending between the plates and having an end portion extending around one end of the plates for directing arc gases in predetermined directions. 100 105

5. The combination with a contact jaw and a switch blade movable into and out of contact therewith of an arc-receiving member conductively connected to and supported from the contact jaw and an arc-quenching 110 device supported thereon comprising a pair of insulating plates disposed on opposite sides of the jaw and between which the switch blade passes, and an arc-quenching metal plate supported therebetween and 115 provided with an opening through which the switch blade passes.

6. The combination with a contact jaw and a switch blade movable into and out of contact therewith, of an arc-quenching device comprising a plurality of spaced metal plates having an opening through which the switch blade passes, and insulating supporting members on opposite sides of the plates having openings registering with the 120 spaces between the plates for the discharge of arc gases accumulating between the plates. 125

7. The combination with a contact jaw and a switch blade movable into and out of contact therewith, of an arc-quenching de- 130

vice comprising a plurality of spaced metal plates having an opening through which the metal blade passes, the said plates being of increasing length from the plate nearest to

5 the contact jaw to the outermost plate.

8. In a circuit interrupter, a contact member and a movable switch member, an arc extinguishing structure including a plurality of conducting plates having open spaces therebetween and provided with slots extending inwardly from one edge and through which said movable switch member passes, means of insulating material extending along the sides of and supporting said plates,
- 10 15 said insulating means also extending along one end of said plates and at least partially closing the spaces between the plates at that end, and the open spaces at the edges of the plates at the other end being unobstructed.
- 20 9. In a circuit interrupter, a contact member and a movable switch member, an arc extinguishing structure including a plurality of conducting plates having open spaces therebetween and provided with slots ex-
- 25 30 35 tending inwardly from one edge and through which said movable switch member passes, means of insulating material extending along the sides of and supporting said plates, said insulating means also extending along the slotted end of the plates and substantially enclosing the spaces between the plates at that end except at the slot through which the blade passes, and the open spaces at the edges of the plates at the other end being unobstructed.

35 In testimony whereof, I have hereunto subscribed my name this 26th day of March, 1928.

OLIVER S. JENNINGS.
